UNITED STATES PATENT OFFICE.

ERIK WESTBERG, OF GEOFF, NORTH DAKOTA.

DRILLING-MACHINE.

No. 852,046.

Specification of Letters Patent.

Patented April 30, 1907.

Application filed July 7, 1906. Serial No. 325,125.

To all whom it may concern:

Be it known that I, ERIK WESTBERG, a citizen of the United States, residing at Geoff, in the county of Walsh and State of North Dakota, have invented certain new and useful Improvements in Drilling-Machines; and I do hereby declare the following to be a full, clear, and exact description of the invention, such as will enable others skilled in the art 5 to which it appertains to make and use the same.

My invention relates to new and useful improvements in drills and more particularly to that class adapted to be used in drilling metal and my object is to provide means for automatically lowering the drill while in motion.

A further object is to provide suitable means for manually operating the drill and a 20 still further object is to provide means for elevating the drill point and parts operating the same when through drilling.

Other objects and advantages will be hereinafter referred to and more particularly 25 pointed out in the claims.

In the accompanying drawings which are made a part of this application, Figure 1 is an elevation, partly in section, showing my improved drill ready for use, and, Fig. 2 is a 30 sectional view as seen from line 2—2 Fig. 1.

Referring to the drawings in which similar reference numerals designate corresponding parts throughout the several views, 1, indicates a shelf or platform which is adapted to 35 be secured to any convenient point as to the wall of a building, by means of brackets 2.

Extending vertically through the shelf is a tubular socket 3, said socket having wings 4 thereon which fit in suitable ways 5 in the 40 shelf and by which means said tubular socket is prevented from rotating. Disposed through the tubular socket 3 is a tubular shaft 6, said shaft being reduced at both ends to form shoulders 7 and 8 against which are 45 adapted to rest bearing balls 9, the balls on the shoulder 8 being held in position by means of a collar 10 while the balls engaging the shoulders 7 are held in place by means of a flange 11 at the lower end of the tubular 50 socket 3. A drill engaging shaft 12 is disposed through the tubular shaft 6 and extends beyond each end thereof, the lower end of the shaft having a socket therein adapted to receive a drill 13, said drill being held in 55 the socket by means of a set screw or the like 14 while the upper end of the shaft 12 is pro-

vided with a balance wheel 15. The drill shaft 12 is longitudinally movable through the tubular shaft 6 and is caused to rotate therewith by means of a lug 16 integral with 60 the tubular shaft 6 engaging a longitudinal groove 17 in the shaft 12. While the shaft 12 is caused to rotate with the shaft 6 it is left free to move longitudinally therein owing to the elongation of the groove 17. 65

Secured to the upper end of the shaft 6 by means of a set screw or the like 18 is a gear 19, with which meshes a gear 20, said gear being in turn mounted upon a vertically disposed shaft 21 which is rotatably mounted 70 in a tubular socket 22, said socket being constructed in the same manner as the tubular socket 3. A head 23 having one or more teeth 24 is secured to the lower end of the shaft 21, the teeth on said head being designed 75 to intermittently engage the teeth upon a feed nut 25, said feed nut being disposed upon the threaded portion of the drill engaging shaft 12 so that when the feed nut is rotated in one direction the drill will be directed 80 downwardly.

An operating shaft 27 is disposed through a tubular socket 28 and is provided at its lower end with a crank arm 29, to which is secured one end of a pitman 30, the opposite 85 end of said pitman being secured to a crank pin 31 carried by the head 23 so that when the shaft 27 is operated the head 23 will be rotated. Disposed on the upper end of the shaft 27 is a lever 32 by which means motion 90 is imparted to said shaft.

In operation the article to be drilled is disposed below the drill 13 after which motion is imparted to the operating shaft 27 through the medium of the lever 32, the crank arm 29 being so constructed that by giving the shaft 27 a substantially half turn, the crank pin 31 will be disposed past the center when the lever 32 may be returned to its initial point thereby giving the shaft 21 a complete revolution and by this construction it will be seen that by moving the lever 32 to the right and left that the continuous rotation of the shaft 21 will be accomplished without imparting complete rotation of the shaft 27. 100 Through the medium of the gears 19 and 20 motion will be imparted to the tubular shaft 6 which causes the shaft 12 carrying the drill 13 to rotate and as the gear 19 is much smaller than the gear 20 the shafts 6 and 12 105 will be rapidly rotated. With each revolution of the head 23 the teeth thereon are di-

rected into engagement with the feed nut 25 thereby checking the rapid rotation of said nut, and causing the same to be turned on the threaded portion of the shaft 12 and directing the same downwardly from the fact that the feed nut 25 is disposed against the lower end of the tubular shaft 6 and is normally held there-against by means of a spring 33 encircling the shaft at a point between the balance wheel 15 and the upper end of the tubular shaft 6. When the drilling has been completed the head 23 is turned until the teeth 24 are out of engagement with the teeth upon the feed nut 25 when said feed nut 15 may be rotated in the opposite direction so that the shaft 12 may be vertically raised and the drill disengaged from the work, the shaft 12 being elevated by means of the spring 33. While I have shown the head 23 as having 20 teeth thereon, at one point, only, it will be readily understood that any number of sets of teeth may be placed around the periphery of the head to increase the feeding capacity of the nut 25 and adapt the same for use in 25 connection with various tempered metals.

It will now be seen that I have provided a drill which may be very cheaply constructed and very efficient in its operation and by providing the multiplicity of shafts and gear- 30 ing it will be seen that the drill may be rapidly rotated with the employment of a small amount of manual labor.

What I claim is:

1. A drill of the class described comprising a shelf, a vertically extending tubular socket disposed through an opening in said shelf, wings on said socket engaging ways in the shelf to prevent rotation of the socket, a flange at the lower end of said socket, a tubular shaft extending through said socket, the

upper and lower ends thereof being reduced to form shoulders, a collar surrounding the reduced upper end of the shaft, a grooved drill shaft longitudinally movable in said tubular shaft, a lug on said tubular shaft adapted to engage the groove in said drill shaft, whereby the drill shaft may move longitudinally in the tubular shaft and be caused to rotate therewith and means to move said drill shaft longitudinally in said tubular 50 shaft.

2. A drill of the class described comprising a shelf, a socket in said shelf, a tubular shaft in said socket, bearings for said shaft, a drill shaft extending through said tubular shaft 55 and having its lower end exteriorly threaded, means to rotatably secure said shafts together, a gear at the upper end of said tubular shaft, a feed nut provided with teeth engaging the threaded end of said drill shaft, a vertically disposed shaft 21 parallel with said drill shaft, a socket for said vertically disposed shaft, a gear at the upper end of said vertically disposed shaft adapted to mesh with the gear at the upper end of said tubular 65 shaft, an interrupted gear at the lower end of said vertically disposed shaft adapted to intermittently engage said feed nut and check the revolution of the same whereby the drill shaft will be lowered and means to rotate said vertically disposed shaft whereby the tubular shaft and parts carried thereby will be operated.

In testimony whereof I have signed my name to this specification in the presence of 75 two subscribing witnesses.

ERIK WESTBERG.
